RAILWAY RAIL

Albert J. Brinkman, Brooklyn, N. Y.

Application July 26, 1938, Serial No. 221,276

4 Claims. (Cl. 238—122)

The present invention relates to novel and useful improvements in railway rails.

Objects and advantages of the invention will be set forth in part hereinafter and in part will be obvious herefrom, or may be learned by practice with the invention, the same being realized and attained by means of the instrumentalities and combinations pointed out in the appended claims.

10 The invention consists in the novel parts, construction arrangements, combinations and improvements herein shown and described.

15 The accompanying drawing, referred to herein and constituting a part hereof, illustrates embodiments of the invention, and together with the description, serves to explain the principles of the invention.

Of the drawing:

Figures 1, 2 and 3 of the drawing are transverse sectional views showing modified embodiments of the present invention; and,

Figure 4 is a similar sectional view showing the rail in accordance with my present invention at a joint and its relation to a splice bar.

25 The present invention has for its object the provision of a novel and improved railway rail which is not subject to ready breakage from transverse fissures. A further object is the provision of a rail in which a major portion of its strength is retained even after a failure has developed so that the danger of sudden failure in service is substantially eliminated.

In accordance with the present invention, the rails are provided with a head portion and a flange connected together with a vertical web, and at a point just under the head, the vertical web is provided with laterally extending fins which form a deep narrow groove with the head, thereby adding to the beam strength of the rail, 35 and at the same time providing a member which retards the development and enlargement of any transverse fissure which would otherwise cause the rail to break in two.

40 Referring now in detail to the illustrative embodiment of the invention as shown in Figure 1 of the drawing, there is provided a rail having a bottom flange portion 10 of conventional construction which extends upwardly into the web 12 and is provided on the top of the rail with a head 14. On the outside of the head, at the left of Figure 1, the head is gradually curved underneath to a point in line with the vertical extension of the rail web 12 and meets with the upper surface of the outside lateral fin 16. Fin 16 45 is formed integrally with the rest of the rail and

is of gradually diminishing thickness outwardly. At the point where the fin 16 meets the head 14 on the top of the fin and meets with the web 12 on the under side of the fin, the surface is curved so as to eliminate any tendency to break at that point. On the inside of the rail, the head extends a little lower than on the outside and in line with the vertical extension of the web it meets with a shorter laterally extending fin 18 which is also of outwardly diminishing thickness, 5 and is likewise curved at the points where it meets with the head and the web. Thus the fins 16 and 18 form a narrow V-shaped groove at each under side of the head 14. Fin 18 is shown as being within the inside of the rail head 14 so that it 10 cannot interfere with the flange on the car wheel 15 20.

If the head 14 and the web 12 are of usual weight, any transverse fissure which develops in the head 14 will be prevented from being extended 25 into the web 12 by means of the fins 16 and 18 which continue to give strength to the rail and, due to their shape and location, render the rail safe for further use.

The principal causes of transverse fissures are 30 the cold rolling action of the wheels and the internal compressive strains set up in the peripheral metal of the rail head during fabrication. Furthermore, the shape of the rail head and fins tends to give improved cooling of the 35 rail during rolling as the rail head may be made relatively shallow.

Figure 2 shows a modified form of the rail of the present invention and in this form, the head 14' of the rail is lighter and the inner fin 18' 35 extends inwardly for a greater distance. Such a rail may be used for tangents while the rail of Figure 1 is more suitable for curves.

Figure 3 shows a further modification in which the outer fin 16'' is formed integrally with the 40 head 14'' of the rail.

The rail shown in Figure 4 is comprised of a head portion 24 and a flange 10 joined together by a vertical web 12 which is provided with fins 26 and 28 extending laterally from the sides of the 45 web 12 and separated from the rail head by means of the narrow and relatively deep slots 32 and 33. These slots and lateral fins serve to improve the cooling characteristics of the rail during the rolling process, and also serve to 50 localize any transverse fissures which might otherwise result in complete fractures of the rail head. At the ends of the rail, the slots 32 or 33 are filled, as by welding 34, so as to provide greater girder strength and to prevent bending 55

of the fin 28 at the fishing surface. Such a rail is particularly useful where mitred joints are to be used as the mitred joint can be made at a greater angle to the side of the rail, and with 5 this more pointed and longer lengths of rail may be employed.

The invention in its broader aspects is not limited to the specific mechanisms shown and described but departures may be made therefrom 10 within the scope of the accompanying claims without departing from the principles of the invention and without sacrificing its chief advantages.

What I claim is:

- 15 1. A rail comprising a head and a flange portion joined together by a web and a relatively thin and wide longitudinal fin extending laterally from each side of the web to a point beyond the head on at least one side of the web, said fins 20 being positioned relatively close to the head of the rail and each separated therefrom by a deep, narrow slot or groove forming a sharp angle with the under side of the head and providing a slot which may be filled at its ends adjacent to a 25 splice bar.
2. A rail comprising a head and a flange portion joined together by a web and a relatively thin and wide longitudinal fin extending laterally from each side of the web to a point beyond the

head on at least one side of the web, said fins being positioned relatively close to the head of the rail and each separated therefrom by a narrow slot or groove which may be filled at its ends adjacent to a splice bar. 5

3. A rail comprising a head and a flange portion joined together by a web and a relatively thin and wide outwardly tapering, integral longitudinal fin extending laterally from each side of the web to a point beyond the head on at least one side of the web, said fins being positioned relatively close to the head of the rail and each separated therefrom by a narrow slot or groove which may be filled at its ends adjacent to a 10 splice bar. 15

4. A rail comprising a head and a flange portion joined together by a web and a relatively thin and wide outwardly tapering, integral longitudinal fin extending laterally from each side of the web to a point beyond the head on at least one side of the web, said fins being positioned relatively close to the head of the rail and each separated therefrom by a narrow slot or groove which may be filled at its ends adjacent to a splice bar, 20 the fin on the inside of the rail lying just below 25 the wheel flange while the fin on the outside of the rail lies above the other fin. 25

ALBERT J. BRINKMAN.
